UNITED STATES PATENT OFFICE.

EMMER F. GWYNN, OF PITTSBURGH, PENNSYLVANIA.

GAS-BURNER.

1,122,740.

Specification of Letters Patent. Patented Dec. 29, 1914.

Application filed April 11, 1910. Serial No. 554,882.

To all whom it may concern:

Be it known that I, EMMER F. GWYNN, a citizen of the United States, and a resident of Pittsburgh, in the county of Allegheny and State of Pennsylvania, have invented a new and useful Improvement in Gas-Burners, of which the following is a specification.

This invention relates to certain new and useful improvements in fuel burners and relates more particularly to that type of burner employed for burning gas for fuel.

Certain objects of the invention are to provide means whereby the fuel may be economically used, and new and novel means for thoroughly mixing the fuel and air before reaching the combustion chamber.

A further object is to provide novel and effective means of regulating the volume of fuel admitted to the air tube or mixing chamber without effecting its velocity, and to feed the fuel into the burner preferably spirally or at any desired angle to the longitudinal axis or radius of the air tube or mixing chamber.

The invention also provides for artificially mixing the air and fuel when the pressure on the fuel or the intensity of the draft is not sufficient to accomplish the desired results, and for this purpose preferably steam or air under pressure is discharged into the air tube or mixing chamber through the valve stem and piston which is employed in the fuel tube for controlling the volume of fuel admitted to the air tube or mixing chamber. This steam or compressed air is discharged preferably with a spiral or rotary motion but may be discharged at any desired angle to the longitudinal axis or radius of the air tube or mixing chamber.

With the above and other objects in view, the invention comprises a novel combination of parts so arranged as to secure a perfect mixture of the fuel and air, as herein-after more specifically described and as illustrated in the accompanying drawings.

In the drawings Figure 1 is a longitudinal section through one form of burner embodying my invention, the sections at the perforations being shown on the line 1-1, Fig. 2; Fig. 2 is a cross section through the fuel tube on the line 2-2, Fig. 1; Figs. 3 and 4 are longitudinal sections through other forms of fuel tubes also embodying the invention; Fig. 5 is a longitudinal section through another form of burner embodying the invention; and Fig. 6 is a

cross section through the fuel tube on the line 6-6, Fig. 5.

In the drawings the numeral 1 indicates a suitable mixing tube, which may be of any desired shape in cross section, and which preferably tapers somewhat toward its inner end 2. The outer end 3 thereof is open to the atmosphere for taking in the necessary amount of air. In this mixing tube 35 is located the fuel tube 4, which has connected thereto the gas supply pipe 5, shown as opening through the side of the mixing tube. The outer end of tube 4 is closed by means of cap 6, through which extends the rod 7 of piston 8, which closes the tube, having such a tight fit therein that practically no gas can escape between the same and the inner walls of the tube. The rod 7 has a threaded connection with the cap 6, and at its outer end is provided with a suitable hand wheel 9 or other means for rotating the same to adjust the position of the piston. The cap 6 is also provided with a stuffing box 10 to prevent leakage of gas.

The arrangement of ports and passages with reference to the piston 8 and tube 4 may vary considerably. As shown in Figs. 1 and 2, the inner end of the fuel tube 4 is practically closed, thereby forming a chamber 30 within said tube in advance of the piston, and the side walls of the tube are provided with a series of ports or perforations 12. These are preferably inclined, not only in the plane of the axis of the tube, but also in the transverse plane of the tube, so that they tend to give to the gas a spiral outward movement. The piston 8 has a plain outer face, and serves as an adjustable means to vary the volume of gas passing through the burner, this being accomplished by adjusting the piston longitudinally in the tube and thus covering more or less of the ports or perforations 12, as is apparent. This adjustment, however, is effected in such a manner that the velocity of the gas passing through the uncovered ports or perforations is not affected, as would be the case with a regulating valve placed, for instance, in the gas supply pipe 5.

It will of course be understood that with the burner described the pressure and quantity of fuel supplied through the gas supply pipe 5 are maintained so that the pressure of the supply at the various ports or perforations 12 is constant, irrespective of how many or how few of these ports or per-

forations are covered or uncovered. Consequently the velocity of the gas passing through these ports is always the same although the quantity of gas passing through the burner may vary. With a regulating valve placed, as referred to, in the gas supply pipe 5, the pressure and quantity of the gas supply through the ports or perforations is varied when the regulating valve is moved.

Fig. 3 shows a modification wherein the inner end of the tube 4^a is open and the tube itself is otherwise imperforate. In this case the gas ports or passages are formed in the peripheral face of the piston 8^a, being shown as spiral grooves 14 which extend not entirely across the face of said piston, there being a portion 15 of the piston face at the outer side thereof which is not traversed by said grooves or passages. Inside of the tube 4 is a bushing 16, whose outer end is beveled or inclined, as shown at 17. To vary the volume of gas with this form the piston 8^a is adjusted, so that the inclined edge 17 of bushing 16 will expose or uncover the outer ends of more or less of the spiral grooves 14.

Fig. 4 shows a modification of the arrangement shown in Fig. 3 wherein, instead of having grooves in the piston, the inner face of tube 4^b is provided with the spiral grooves 18, which begin at various points lengthwise of the tube, while the piston has a plain or ungrooved face, and having a tight fit in the tube, as in Fig. 1. By adjusting the piston longitudinally in the tube the outer ends of more or less of the grooves 18 are uncovered, so as to vary the volume of gas but without changing its velocity. To insure the drawing in and thorough mixing with the gas of a sufficient supply of air in case the pressure of the gas falls so low as not to draw in a sufficient quantity of air, I provide means for discharging a fluid pressure medium into the air tube or mixing chamber. As shown in Fig. 1, a supply pipe 20 for steam, compressed air, or other fluid pressure medium, connects with a port 21 leading to chamber 22 in cap 6. A port or passage 23 extends axially through the piston stem 7, opening through the side of said stem inside of the chamber 22 and extends through the piston 8 so as to deliver the steam or air beyond said piston into the chamber 30. The end of the tube 4 is provided with a series of ports or openings 24, which lead outwardly from the chamber 30, and through which the steam or air introduced through the piston 8 escapes, preferably somewhat tangentially or spirally, and thereby induces a sufficient velocity of the gases to draw in the required amount of air for securing the proper mixture of gas and air.

In Fig. 3 the port or passage 23 through piston stem 7 communicates in the piston 8

with a series of radially and outwardly extending passages or ports 25 opening into the spiral grooves 14 in the face of said piston near the inner ends of said grooves. The effect of the steam or compressed air in this case is to impart a higher velocity to the gas escaping through the spiral grooves 14, which results in drawing into the mixing tube the requisite amount of air.

Figs. 5 and 6 illustrate the simplest form of the invention. In this case the fuel tube 4^c is closed at its inner end by suitable means, such as the cap 27, and is provided with a series of ports or perforations 12 which extend through said walls at an inclination to the longitudinal axis of the tube and also to the transverse plane of the tube, so as to impart to the gas the requisite spiral motion. The regulating piston is omitted, and instead the supply pipe 5 is provided with a regulating valve 28.

In all of these forms of the invention the gas is preferably given a spiral or whirling outward motion, so as to insure the thorough mixture thereof with the incoming air. The air is drawn in by the action of the escaping gas, and since the velocity of the gas is not affected by any change of volume thereof due to the adjustment of the regulating piston, this insures the drawing into the mixing tube of a sufficient quantity of air to produce perfect combustion.

What I claim is:

1. A fuel burner comprising a hollow body constituting an air tube or mixing chamber, a fuel tube in said hollow body provided through its side walls with a plurality of series of circumferentially spaced perforations arranged longitudinally of the tube and each perforation directing the gas spirally along the tube, and means for covering and uncovering said several series of perforations to control the volume of fuel admitted through the said tube.

2. A fuel burner comprising a hollow body open at both ends and constituting an air tube or mixing chamber, and a fuel tube in said hollow body having a chamber at its inner end and provided with ports or passages through its side walls arranged at an angle to both the radius and the axis of the air tube or mixing chamber.

3. A fuel burner comprising a hollow body constituting an air tube or mixing chamber, a fuel tube in said hollow body and provided with a plurality of series of circumferentially spaced ports or passages through its side walls arranged at an angle to both the radius and the axis of the tube, a piston closing the inner end of said fuel tube, and means for moving said piston in said fuel tube to cover and uncover said several series of ports.

4. A fuel burner comprising a fuel tube provided with a plurality of ports through

its side walls, a piston in said tube, the walls of said tube being arranged to form a chamber in said tube in advance of the piston, means for moving said piston in said tube to 5 cover or uncover the ports therein, said piston having a passage therethrough for supplying steam or compressed air to said chamber, and the walls of said fuel tube in advance of said piston being provided with 10 ports through which the steam or compressed air escapes from said chamber.

5. A fuel burner comprising a fuel tube provided with a plurality of ports through its side walls, a piston closing said tube, 15 means for moving said piston in said tube to regulate the ports in the tube, a hollow rod or stem extending from said piston, and means for connecting steam or compressed air to said rod or stem.

20 6. A fuel burner comprising a hollow body constituting an air tube or mixing chamber, a fuel tube projecting into said mixing chamber and provided with a plurality of ports or passages through its side 25 walls, a piston closing said fuel tube, and a hollow rod or stem extending from said piston and through which steam or compressed air may be passed.

7. A fuel burner comprising a fuel tube, 30 and a piston fitting therein, one of said parts being provided with a plurality of ports or passages spaced circumferentially around the axis of said tube and arranged to give spiral movement to the fuel, said ports or 35 passages having portions thereof located in the contacting surfaces of said tube and piston and arranged when the piston is moved to be successively covered or uncovered, means for moving the piston in the 40 fuel tube to cover or uncover said ports or passages, and means including a port through said piston for supplying steam or compressed air therethrough.

8. A fuel burner comprising a fuel tube 45 having a plurality of longitudinally spaced series of ports or passages arranged circumferentially and to give spiral movement to the fuel, a piston movable in said tube to successively cover and uncover different series of ports or passages, and means for 50 moving said piston in said tube.

9. A fuel burner comprising a tube and a piston therein, one of said parts being provided with ports or passages arranged to impart a spiral motion to the escaping fuel, 55 said ports or passages being arranged to be successively covered or uncovered as the piston is moved longitudinally, and means for adjusting said piston longitudinally in the tube to thereby vary the volume of fuel. 60

10. A fuel burner comprising a tube arranged at one end for connection to a fuel supply, and a piston at the other end of said tube, one of said parts being provided with ports or passages arranged to impart a spiral motion to the fuel, the open ends of said 65 ports or passages lying between the coöperating faces of the piston and tube, the coöperating faces of the piston and tube being arranged so that when the piston is moved 70 longitudinally more or less of said ports or passages are uncovered, and means for adjusting said piston longitudinally in said tube.

11. A fuel burner comprising a tube arranged at one end for connection to a fuel supply, a piston fitting and movable within said tube, said tube being provided in its side walls with ports or passages opening into the interior of the tube at different points 75 along the length thereof, and means controllable through the supply end of said tube for adjusting said piston longitudinally of the tube to successively cover or uncover 80 said ports or passages.

12. A fuel burner comprising a mixing tube, a fuel tube projecting thereinto, a piston closing said fuel tube, said fuel tube and piston being formed to provide ports or 85 passages arranged to impart a spiral motion to the fuel, the coöperating faces of said tube and piston being arranged so that when the piston is moved in the tube said ports or 90 passages are uncovered successively, and means for adjusting said piston longitudinally in said tube. 95

In testimony whereof, I have hereunto set my hand.
